POWER SAW FOR DEHORNING LIVESTOCK OR SIMILAR ARTICLE

Judson R. Wynkoop, Canal Winchester, Ohio

Application December 21, 1951, Serial No. 17,791

Term of patent 14 years

(Cl. D93—3)

To all whom it may concern:

Be it known that I, Judson R. Wynkoop, a citizen of the United States, residing at Canal Winchester, in the county of Franklin and State of Ohio, have invented a new, original, and ornamental Design for a Power Saw for Dehorning Livestock or Similar Article, of which the following is a specification, reference being had to the accompanying drawings, forming a part thereof.

Fig. 1 is a top plan view of a power saw for dehorning livestock or similar article showing my new design;

Fig. 2 is a side elevational view of one side thereof;

Fig. 3 is a similar view of the opposite side;

Fig. 4 is a front elevational view;

Fig. 5 is a rear elevational view; and

Fig. 6 is a slightly reduced bottom plan view.

I claim:

The ornamental design for a power saw for dehorning livestock or similar article, substantially as shown.

JUDSON R. WYNKOOP.
